UNITED STATES PATENT OFFICE.

JOHN C. HACKETT, OF ST. LOUIS, MISSOURI.

WRENCH.

No. 825,720

Specification of Letters Patent

Patented July 10, 1906.

Application filed October 5, 1904. Serial No. 227,297.

To all whom it may concern:

Be it known that I, JOHN C. HACKETT, a citizen of the United States, and a resident of St. Louis, Missouri, have invented certain

5 new and useful Improvements in Wrenches, of which the following is a specification containing a full, clear, and exact description, reference being had to the accompanying drawings, forming a part hereof.

10 My invention relates to improvements in wrenches; and it consists of the novel features herein shown, described, and claimed.

15 In the drawings, Figure 1 is a perspective of a wrench embodying the principles of my invention with the locking-lever in its unlocked position. Fig. 2 is a reverse perspective showing the locking-lever in its locked position. Fig. 3 is a central sectional detail. Fig. 4 is a perspective, upon an enlarged scale, 20 of the movable jaws and their integral parts. Fig. 5 is a perspective of the gripping-washer.

25 Referring to the drawings in detail, the main frame of the wrench comprises the head 6, having a longitudinally-extending slot 7, the surface around the slot being depressed to form the slideway 8; the jaws 9 and 10, extending upwardly from the head at one end of the slot, said jaws being set at right angles to each other; the handle 11, 30 extending from the opposite end of the head from the jaws, and the crank 12, extending from the handle. The faces of the head opposite the slideway 8 have transverse corrugations 13.

35 The movable jaws and their integral parts comprise the jaws 14 and 15 set at right angles to each other and mating with the jaws 9 and 10, the sliding head 16 forming a base for the jaws 14 and 15 and operating in the 40 slideway 8, the boss 17 extending downwardly from the head 16 through the slot 7, and the screw-threaded locking-post 18 inserted through the boss 17 and held in position by the pin 19.

45 The clamping-washer comprises a circular plate 20, having transverse corrugations 21 to engage the corrugations 13 and having a central opening 22 to receive the post 18 and having a guide-lug 23 extending downwardly 50 into the slot 7, so as to hold the corrugations 21 in their transverse positions.

The locking-lever comprises the nut 24, screw-seated upon the lower end of the post 18 against the washer 20, and the handle 25 55 formed integral with the nut and extending outwardly, so that by moving the handle 25

one way the jaws 14 and 15 are released and may be moved to and fro in the slideway 8, and by moving the handle 25 the other way the movable jaws are rigidly clamped to the 60 head 6.

In assembling the parts care should be taken and the nut 24 should tighten upon the post 18, with the handle 25 approximately at right angles to the handle 11, so that when 65 the handle 11 is held with the left hand and the handle 25 is grasped with the right hand and pushed away from the operator a good leverage is provided for tightening the nut 24 upon the post 18. A hook is formed upon 70 the outer end of the lever 25, said hook being turned backwardly, as shown in Fig. 1, to prevent the hand from slipping off the lever 25 when the lever is pushed to the tight position. The sliding head 16 is slightly tapered, 75 and the post 18 extends downwardly from the forward end of the sliding head. The jaws 14 and 15 are at right angles to the upper face of the sliding head. When the movable jaws are released by loosening the 80 nut 24 and pushed tightly against an axle-nut 26 (shown in dotted lines in Fig. 2) or other similar nut, the forward end of the sliding head will be elevated, and when the handle 25 is operated to tighten the nut 24 85 the forward end of the sliding head will be pulled down firmly upon the slideway 8, thus tipping the movable jaws toward the rigid jaws and firmly grasping the axle-nut, so that when the axle-nut is unscrewed it 90 will be retained and carried by the wrench, thus providing a handle for the operation of the greasy dirty nut and avoiding the necessity of applying the hands directly to the nut. 95

I claim—

In a wrench, the combination with a handle having a longitudinal slot in its forward end and one face of said handle adjacent the sides of said slot being depressed to form a 100 slideway, a jaw integral with the forward end of said handle, and there being transverse teeth formed in the under side of the handle on each side of the slot therein, of a movable jaw a rectangular lug integral with the under 105 side of said jaw arranged to slide in the slideway formed in the slotted end of the handle, a screw-threaded shank rigidly fixed to and projecting downwardly from the rectangular lug through the slot in the handle, there being a recess formed in the under side of the 110 rectangular lug adjacent the shank, a washer

fitted on the shank and provided in its top surface with transverse teeth that engage the teeth formed in the under side of the handle, a rectangular lug integral with the top side 5 of the washer, which lug engages in the recess in the under side of the rectangular lug, a nut mounted upon the screw-threaded shank, and an elongated handle integral with said nut and projecting outwardly therefrom, 10 and the outer end of said handle being bent

laterally to form a handhold; substantially as specified.

In testimony whereof I have signed my name to this specification in presence of two subscribing witnesses.

JOHN C. HACKETT.
